UNITED STATES PATENT OFFICE.

JESSE M. JENNINGS, OF DES MOINES, IOWA.

GUN FOR DESTROYING WIRE ENTANGLEMENTS.

1,275,561.

Specification of Letters Patent. Patented Aug. 13, 1918.

Application filed April 6, 1918. Serial No. 227,124.

To all whom it may concern:

Be it known that I, JESSE M. JENNINGS, a citizen of the United States, and resident of Des Moines, in the county of Polk and

5 State of Iowa, have invented a certain new and useful Gun for Destroying Wire Entanglements, of which the following is a specification.

The object of my invention is to provide 10 a gun for destroying wire entanglements.

More particularly it is my object to provide a gun comprised of two gun members arranged adjacent to each other and adapted to fire projectiles which pick up a chain 15 or similar device and carry it with them for destroying wire entanglements and the like.

A further object is to provide a gun of the kind mentioned, and a projectile for use 20 therewith, the gun members having means for supporting thereon at their muzzles, a chain or similar device, in proper position to be taken up by the projectiles discharged from the muzzles of the gun members, which 25 projectiles have engaging means for seizing and holding such a chain or the like.

Still a further object is to provide such a gun having gun members, and to provide projectiles therefor, the gun members and 30 projectiles having coacting parts so arranged that the engaging means on the projectiles will always leave the gun muzzles at the proper positions for engaging the chain.

Still a further object is to provide such a 35 gun having means for shifting or moving the gun members so that the muzzles may be in a variety of positions with relation to a vertical line.

With these and other objects in view, my 40 invention consists in the construction, arrangement and combination of the various parts of the device, whereby the objects contemplated are attained, as hereinafter more fully set forth, pointed out in my claims, and 45 illustrated in the accompanying drawings, in which:

Figure 1 shows a front elevation of a gun embodying my invention.

Fig. 2 shows a top or plan view of the 50 same, part of the supporting frame being shown in horizontal cross-section.

Fig. 3 shows a side elevation of the same, part of the supporting frame being shown in vertical cross-section.

55 Fig. 4 shows a front end view of the muzzle of one of the gun members.

Fig. 5 shows a side elevation of one of the projectiles.

Fig. 6 shows a sectional, detail view of a portion of a gun barrel.

In the accompanying drawings I have used the reference numerals 10 and 11 to indicate generally two guns or gun members, which may be built very much like ordinary cannon, and are placed side by side, as shown in Figs. 2 and 3.

The barrels of the gun members 10 and 11 are not rifled in the ordinary way, but are provided on their interiors with longitudinal grooves 12, each gun having one 70 groove in the wall thereof adjacent to the other gun.

The gun members 10 and 11 are firmly and rigidly mounted in a comparatively heavy frame 13, which is received for rotation within another frame 14.

The frame 13 is formed with an external annular groove 15, and the frame 14 is provided with an internal corresponding annular groove 16. Mounted in the grooves 15 80 and 16 is a series of roller bearing members 17, preferably mounted on spindles 18 which are mounted in the walls of the frame 14. The frame 14 may be mounted in any suitable way upon the recoil mechanism of a 85 gun carriage.

Mounted on the frame 13 is a large worm wheel 19. Suitably supported on the frame 14 is a worm gear 20, which meshes with the worm wheel 19 and to which rotation 90 may be imparted in any suitable way for rotating the frame 13 and the gun members in the frame 14. It will thus be seen that the gun members 11 and 10 may be arranged in the same horizontal plane or in the same vertical plane, or in a great variety of positions.

At the rear end of the gun members the grooves 12 are deeper for a short distance, as at 21, for a portion of their length equal 100 to the jacket 22 on the projectile 23. Received within the deeper portions 21 are filler strips 24 which are pivoted to links 25. The links 25 are pivoted at the bottoms of the groove portions 21.

When the breech of the gun is opened, the filler strips 24 are swung rearwardly and outwardly, and when the projectile is inserted into the gun and the breech is closed the filler strips 24 are swung upwardly and forwardly until they close the groove portions 21 and prevent the explosion, when the gun

is fired, from forcing any part of the shell cap into said groove portions 21.

On each shell is a hook member 26 which fits the groove 12 snugly enough so as to prevent any substantial waste of power at the time of the explosion.

Secured to each projectile 23 is a short spring 27 inclined toward the top of the hook member 26, for a purpose to be hereinafter mentioned. At the muzzle of each gun there is formed a recess 28 of proper size to receive one of the links of the chain 29.

In the practical use of my improved gun the two gun members are loaded with projectiles such as that shown in Fig. 5, with the hook members 26 received in the grooves 12. A short length of chain 29 is taken to the muzzles of the guns, and the end links, which are preferably round, are placed in the recesses 28, where they then stand in such positions as to overlap portions of the grooves 12 in such a way as to permit the body of the projectile 23 to pass freely from the muzzle of the gun without dislodging the chain links, and also in such a way that when the hook members 26 pass from the muzzles of the guns they enter the end links of the chain so that the projectiles will carry the chain with them.

It should be noted in this connection that the velocity of the projectiles 23 will be such that the spring members 27 will strike the end links of the chain as the projectiles leave the guns, but will be sprung out of the way to permit the hook members 26 to enter said end links; and when the projectiles carry the chain with them from the gun the end links of the chain will be locked to the projectiles until the target is struck.

It will be obvious that a device of this kind, firing two projectiles in a position spaced substantially from each other, which projectiles are connected by a length of chain, will result in striking a barbed wire entanglement with the two projectiles and the chain in such a way as to simply tear through and destroy the entanglement.

The advantages of such a device as this in destroying barbed wire entanglements, are largely obvious from the foregoing description.

The gun is especially adapted for firing for comparatively short distances where the target is within plain sight and the gun can readily be adjusted for tearing down the barbed wire entanglements at any particular point, and leaving a clean path for advancing troops. Incidentally, it may be men-

tioned that the projectiles, after destroying the barbed wire entanglements, continue toward the enemy positions.

It is obvious that changes may be made in the construction and arrangement of the various parts of my device and in the method of mounting my guns on the carriage, without departing from the essential features and purposes of my invention, and it is my intention to cover by my claims any modified forms of structure or use of mechanical equivalents which may be reasonably included within their scope.

It will be understood that suitable mechanism shall be provided for handling the guns on the carriage, operating the breech mechanism and firing the guns simultaneously.

I claim as my invention:

1. A device for destroying wire entanglements, comprising a pair of gun barrels mounted adjacent to each other, said barrels having grooves opening into their bores, means on said gun barrels for supporting a flexible device at their muzzles, projectiles, and engaging devices on said projectiles adapted to travel in said grooves and engage the flexible devices when the projectiles leave the barrels.

2. A device for destroying wire entanglements, comprising a pair of gun members mounted adjacent to each other, each of said members having on its interior a longitudinal groove, and having means at its end for supporting the end of a flexible device in position adjacent to the end of one of said grooves, and filler strips for the rear portions of said grooves, adapted to be out of the way during the loading of the gun, and to close the rear portions of said grooves when the gun is discharged.

3. A device for destroying wire entanglements, comprising a pair of gun members mounted adjacent to each other, each of said members having on its interior a longitudinal groove, and having means at its end for supporting the end of a flexible device in position adjacent to the end of one of said grooves, filler strips for the rear portions of said grooves, adapted to be out of the way during the loading of the gun, and to close the rear portions of said grooves when the gun is discharged, and links for pivotally connecting said filler strips with said gun members.

Des Moines, Iowa, March 8, 1918.

JESSE M. JENNINGS.
